S. A. FREER.
LEATHER PUNCH FOR PLIERS.
APPLICATION FILED DEO. 9, 1913.

1,105,129.

Patented July 28, 1914.

UNITED STATES PATENT OFFICE.

STEPHEN A. FREER, OF EL MONTE, CALIFORNIA.

LEATHER-PUNCH FOR PLIERS.

1,105,129.

Specification of Letters Patent. Patented July 28, 1914.

Application filed December 9, 1913. Serial No. 895,555.

To all whom it may concern:

Be it known that I, STEPHEN A. FREER, a citizen of the United States, residing at El Monte, in the county of Los Angeles and State of California, have invented a new and useful Leather-Punch for Pliers; and I do hereby declare the following to be a full, clear, and exact description of the invention, such as will enable others skilled in the art to which it appertains to make and use the same.

This invention relates to a new and useful leather punch adapted for use between the handles of a pair of pliers or the like.

An object of the invention is the provision of a device of this nature having novel means for holding the punch proper in an open or closed position.

Another feature of the invention is to so construct the holding means, that the same may be operated by the thumb of a hand to release the punch from an open position, and when released, the fore finger of the same hand may be used for closing the punch.

Another feature of the invention is the provision of simple and efficient means for connecting the base of the punch firmly to one of the handle members.

In practical fields the details of construction may be subjected to alterations, falling within the scope of what is claimed.

The invention comprises further features and combination of parts, as hereinafter set forth, shown in the drawings and claimed.

In the drawings: Figure 1 is a view in perspective of the improved punch as applied to one of the handle members, illustrating in dotted lines how the holding means may be operated and the punch thrown to a closed position. Fig. 2 is a sectional view longitudinally through the structure. Fig. 3 is a similar view showing the punch closed. Fig. 4 is a transverse sectional view. Fig. 5 is a longitudinal fragmentary sectional view through the punch showing a different form of means for connecting the base of the punch to one of the handle members.

Referring more particularly to the drawings, 1 and 2 designate two jaw members, which constitute a pair of pliers. The jaw member 1 is constructed with an elongated slot 3, each end of which is almost circular,

as shown, while the intermediate portion of the slot is restricted, and the walls of this restricted portion, which are designated by the numeral 5, are straight. A pivot pin passes through this slot and is anchored in any suitable manner to the jaw 2. The part 6 (which passes through the slot) of the pivot pin 6 is rectangular in contour, and is of such a shape and construction that when the jaw members are opened, the jaw member 1 may be adjusted that one circular end 65 or the other of the slot may engage the rectangular shape of the pivot pin.

The jaw members terminate in handle members 8 and 9, the handle member 9 having a flat portion 10, while the handle member 8 is constructed with shoulders 11 at the ends of the recess 12. Each side of the handle member 8 is constructed with an overhanging spring flange 13. A trough-shaped holder having flanges 14 is provided, 70 and is adapted to be inserted in the recess between the shoulders 11, so that the flanges 14 will engage under the flanges 13, thereby holding the holder in place. Pivoted upon the pin 15 between the sides 16 of the holder 80 17 is a leather punch member 18, the cutting edge 19 of which being adapted to punch or cut a hole in the piece of leather, when the same is placed between the cutting edge and the flat portion 10 of the jaw 9. The piece 85 that is cut from the leather passes through the hollow portion of the punch, and discharges from the lower end 20 of the hollow part. Adjacent the lower end 20 of the hollow part, the punch is provided with a 90 recess 21, so that the pieces cut from the leather may easily leave the hollow part. Riveted or otherwise secured in the holder at one end, as shown at 22 is a leaf spring 23. Adjacent to the free end of the leaf 95 spring is an aperture 24 to receive a lug 25 of the lower end of the punch, to hold the punch in an open position. When the leaf spring is depressed at the free end, the punch may be closed as shown, the spring 100 engaging the part 26 to hold the punch closed. Extending laterally from the free end of spring is a finger piece 27, whereby the spring may be depressed by the thumb of one hand, while the fore finger of the 105 same hand may be used to throw the punch from an open position to a closed position, as shown in dotted lines in Fig. 1. In Fig.

5, however, the holder is riveted as shown at 28 in the recess 12 between the shoulder 11.

The invention having been set forth, what 5 is claimed as new and useful is:—

In combination with a pair of pivoted members, one acting as a support, the other acting as an abutting member, a trough-shaped holder having dovetail connections 10 with the support to hold the holder thereto, a leather punching member pivoted in the holder adapted to coöperate with the abutting member, the lower end of the punch having a lug, and a leaf spring secured in

the holder and having an aperature in the 15 free end to receive said lug to hold the punch in an open position, said leaf spring adapted to engage the end of the punch having the lug to hold the punch in an open position.

In testimony whereof I have signed my name to this specification in the presence of 20 two subscribing witnesses.

STEPHEN A. FREER.

Witnesses:

F. P. SAPPINGTON,
A. B. ENDICOTT.
